UNITED STATES PATENT OFFICE.

ALFRED E. SMITH, OF NEW BEDFORD, MASSACHUSETTS.

DECORATION OF LAMP-SHADES.

SPECIFICATION forming part of Letters Patent No. 230,581, dated July 27, 1880.

Application filed April 8, 1880. (No model.)

To all whom it may concern:

Be it known that I, ALFRED E. SMITH, glass-decorator, a citizen of the United States, residing at New Bedford, in the county of Bristol and State of Massachusetts, have invented 5 certain new and useful Improvements in the Decoration of Lamp-Shades; and I do hereby declare the following to be a full, clear, and exact description of the invention, such as will 10 enable others skilled in the art to which it app pertains to make and use the same, reference being had to the accompanying drawings, and to letters or figures of reference marked thereon, which form a part of this specification.

15 My invention relates to a new and useful improvement in the decoration of lamp-shades, whereby I produce a new effect, as more fully described hereinafter, reference being had to accompanying drawings.

20 Heretofore lamp-shades in general use, when made and ornamented by enamel or other decorations, have only had such decorations on the outer surface, and owing to the form the beauty and effect is to a great extent lost or 25 wasted, as the decorations cannot be seen when the shades are raised above the head, as is the case when used on chandeliers or in cars, where they are fixed high up to reflect and distribute the light.

30 In the drawings, Figure 1 is a vertical elevation of my illuminated lamp-shade, and Fig. 2 is an elevation of my lamp-shade broken away to show its interior decorations.

35 A marks decorations of the lamp-shade on the exterior surface, and B represents decorations on its interior surface, which are adapted to combine therewith and form a new and complete entity.

40 When the decorations are formed on the interior surface a shadow is projected upon its

exterior surface, which is plainly visible to the eye, even when the shade is elevated. Besides, the light projects across the lines of the figure before leaving the shade, and thereby illuminates them, and thus a softer light and in all 45 respects a more pleasing effect is produced.

By this construction the heavy lines *a* may be placed upon the interior surface of the lamp-shade and the finer lines *b* upon its exterior surface, and the broad interior lines may be 50 tinted to produce a pleasing effect in connection with thinner exterior lines of a different hue. Besides, the white glare from the ordinary lamp-shade may thus be mellowed and a pleasing and beautiful effect produced by 55 the reflected colors.

These decorations may be made in delicate tracings, or in any suitable manner or form to embrace all or a part of the interior and exterior surfaces of the shade.

60 It is found in practice that the interior portions of the lamp-shade when decorated with reference to its exterior decorations produce a new and beautiful effect without appreciably limiting the exterior reflecting-surface, and 65 when the lamp-shade is placed in position the whole decoration is visible.

Having described my improvement, what I 70 claim as new, and desire to secure by Letters Patent, is—

A lamp shade or reflector having the interior decorations, B, and the exterior decorations, A, in combination, substantially as shown, and for the purpose described.

In testimony whereof I affix my signature in 75 presence of two witnesses.

A. E. SMITH.
